(57) **CLAIM**

The ornamental design for a watch, as shown and described.

DESCRIPTION

FIG. 1 is a front view of a watch;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a magnified view of a portion thereof.

The watch band is shown in a different position in FIGS. 3 through 6. FIGS. 3 through 6 are shown on a larger scale than FIGS. 1 and 2.
